UNITED STATES PATENT OFFICE.

BENGT M. W. HANSON, OF HARTFORD, CONNECTICUT, ASSIGNOR TO PRATT & WHITNEY COMPANY, OF HARTFORD, CONNECTICUT, A CORPORATION OF NEW JERSEY.

METAL REDUCING MACHINE.

No. 905,523.

Specification of Letters Patent.

Patented Dec. 1, 1908.

Application filed May 5, 1908. Serial No. 431,048.

To all whom it may concern:

Be it known that I, BENGT M. W. HANSON, a citizen of the United States, residing at Hartford, in the county of Hartford and State of Connecticut, have invented certain new and useful Improvements in Metal-Reducing Machines, of which the following is a specification.

This invention relates to metal-reducing machines one of the primary objects of the invention being to provide simple and effective means for quickly obtaining access to the work for caliper and other purposes.

A metal-reducing machine embodying my invention can be used with advantage in many different connections for instance grinding various articles. The invention possesses other features of utility in addition to that to which brief allusion has been made and all of these will be fully set forth in the following description of that form of embodiment of the invention incorporated in the machine illustrated in detail in the drawings accompanying and forming part of the present specification.

Referring to said drawings, Figure 1 is a side elevation of a machine involving my invention. Fig. 2 is an end elevation of said machine, the bed and slide being in transverse section. Fig. 3 is a horizontal sectional top plan view of the tool-supporting member and certain adjunctive devices. Fig. 4 is a section on the line 4-4 Fig. 3 looking in the direction of the arrow.

Like characters refer to like parts throughout the several figures of the drawings.

Referring first to Figs. 1 and 2 the numeral 2 denotes the bed of a metal reducing machine in which my invention may be advantageously embodied. On this bed I have shown as mounted a carrier as 3 which may consist of a slide mounted to travel longitudinally of said bed 2, the latter being provided with suitable ways for the slide. In connection with the latter I may provide guards as 4 and 5. These guards and the results achieved thereby are novel but the former are not claimed herein but are made the basis of a co-pending application Serial No. 432,095 filed May 11, 1908. The bed 2 may be provided with a suitably-operated pinion as 6 meshing with a rack as 7 fastened to the underside of the slide 3 which presents a simple means for moving said slide backward and forward as occasion may require.

The machine comprises two members one of which may support the work and the other of which may support the tool of whatever character these parts may be. The work-holder or support shown in the drawings is designated by 8 and it may consist of a face-plate or chuck suitably mounted and to which the work may be connected in any desirable manner. The tool-supporting member is denoted in a general way by 9 and in the present instance is movable relatively to the work-supporting member 8. Preferably the tool-supporting member is mounted for swinging movement by reason of which it can be readily moved into or out of operative relation.

The tool-supporting member 9 includes in its make up an arm as 10 which is represented as being hollow, and as having openings near its inner end to receive bushings 75 or sleeves as 11 and 12. The bushings 11 and 12 are rigidly connected to said arm 10 in any suitable manner for example by pins as 13 in each case. Said bushings therefore swing with said arm or tool-support proper, 80 and they may be mounted in any desirable way, for illustration by means of bearings as 14 rising from the slide 3.

The two bushings are represented as rotatively supporting a shaft as 15 from which 85 as will hereinafter appear the tool receives its motion. It will be evident that the arm 10 can be freely swung up or down without affecting said shaft 15; the two parts however move about the same axis.

The shaft 15 may be turned in any suitable manner, for example by the cone-pulley 16 fastened to one end thereof and connected by a belt as 17 with a cone-pulley as 18 fastened on the shaft of a motor as 19 mounted 95 in some fixed manner on the slide 3. The motor 19 is shown as being of the "electric" type.

The swinging arm 10 rotatively supports at its outer end a tool-spindle as 20 to which 100 is fastened within said arm a pulley as 21 of comparatively small diameter connected by a belt as 22 with a pulley as 23 of larger diameter fastened to the shaft 15 by reason of which said tool-spindle can be turned at 105 a high speed. The tool-spindle and its co-operating parts are also of novel construction but are not claimed themselves herein but are made the basis of a separate application filed May 5 1908 Serial No. 431,049. 110

The tool-spindle 20 it might be stated consists of a sectional quill, the outer section of which carries the tool 24, and which is removably fitted in a sleeve as 25 clamped by 5 a clamping-member as 26 carried by the hub 27 at the outer end of the swinging arm 10, the tool-spindle or sectional quill extending through said hub. It will be obvious that when the motor 19 is thrown into action the 10 tool 24 through the intermediate parts will be caused to rotate. By retracting the slide 3 from the position in which it is shown in Fig. 1 a sufficient distance the tool can be withdrawn from the work after which as 15 will hereinafter appear the arm 10 may be swung up. The work connected with the face-plate or chuck 8 is hollow and the tool is introduced into the work for reducing the interior thereof. As reduction in the 20 interior diameter of the work progresses it is necessary from time to time to internally caliper the work; by moving the slide 3 backward and then swinging the arm 10 upward the operation of caliper 25 or measuring the inside diameter of the work is materially facilitated. After caliper 25 of the work has been concluded the arm 10 will be swung down and then held following which the slide 3 will be advanced to carry the tool 24 into the work. The slide 3 can be reciprocated and the arm 10 can be swung up without stopping the tool 24.

Means are provided for holding the arm 10 in its operative relation in a positive certain manner and those shown for this purpose will now be set forth. The arm 10 is shown as provided with a downwardly curved or overhanging portion 29 terminating in a casing as 29' for a latch as 30 sliding in said casing and co-operative with a horn or projection as 31 extending outwardly from the slide 3. The latch 30 is represented as bored longitudinally to receive a coiled push spring as 32 bearing at its forward 35 end against said latch and at its rear against a screw or removable plug as 33 threaded into the outer portion of said casing 29'. The spring at all times holds said latch in its working position and moves it toward 40 such position when it is released.

Any suitable means may be provided for retracting the latch 30 for example rack and pinion means, the latch being illustrated as provided with a rack as 34 engageable by a 45 pinion as 35 fixed to a shaft or pin as 36 rotatively supported by the arm 10 near the outer end thereof. The shaft 36 may be manually-operated in any suitable way for example by means of an arm as 37 attached 50 thereto. By swinging the arm 37 in the proper direction the latch 30 through the intervening parts can be drawn back to disengage the head of such latch from the horn or projection 31 to free the arm 10 and permit upward swinging movement thereof, it

being clear that prior to the point the latch is thus engaged the slide 3 is retracted a distance sufficient to carry the tool 24 out of the work. When the arm 10 is thus swung upward the interior of the work can be 70 inspected and seen, said arm being wholly out of the way as shown best by dotted lines in Fig. 4.

There is considerable weight at the outer end of the arm 10 and I provide means in 75 connection with said arm which facilitates its upward swinging movement. The force applied by said means need not necessarily be sufficient to lift the arm without the aid of the operator but need simply be sufficient 80 to counterbalance the arm and the parts sustained thereby so that it is a simple and easy matter for the attendant of the machine to lift the arm prior to caliper 85 or measuring. I will now set forth the means illustrated for accomplishing the result in question.

Within a passage as 38 in the slide 3 is an automatically-operable member as the plunger 39 which reciprocates transversely of said slide and which in the present case is 90 operative by spring means such for example as the coiled push spring 40 located in said passage 38 and bearing at one end against the plunger 39 and at the other against a screw-plug as 41 removably fitted in the 95 outer end of said passage 38. There is therefore at all times a lifting force applied to the arm 10 which is normally resisted by the latch 30.

The plunger 39 has a rack 42 meshing with 100 a segment as 43 forming part of the bushing 11. The latter and the segment may if desired be made integral. The spring-operated plunger 39 tends constantly to apply through the intermediate parts an upwardly swinging action to the arm 10; the latter during grinding being positively held by the latch 30.

It will be assumed that the tool 24 is within the work as shown in Fig. 1, that the motor 19 is in action and therefore that the tool is rotating. The interior of the work can then be ground or reduced. It will be further assumed that the operator desires to caliper the work. To accomplish this the 115 slide 3 is drawn back sufficient to carry the tool from the work at which point the latch 30 will be drawn back by the manipulation of the arm 37 thereby wholly freeing the swinging arm 10 whereby the latter can be 120 quickly swung upward to attain the desired end, said arm moving about the driving shaft 15 as a pivot.

I do not restrict myself to the exact disclosure made by the accompanying drawings 125 and the hereinbefore description of the same as certain variations may be adopted within the scope of my claims.

What I claim is:

1. A machine of the class described com- 130

prising two members one of which constitutes a work-support and the other a tool-support and one of said members being movable with respect to the coöperating member, 5 and automatically-operative means tending to shift said movable member into an inoperative position with respect to the companion member.

2. A machine of the class described comprising two members one of which constitutes a work-support and the other a tool-support and one of said members being movable with respect to the coöperating member, automatically-operative means tending to 10 operate said movable member, and means for normally holding said movable member against movement.

3. A machine of the class described comprising two members one of which constitutes a work-support and the other a tool-support and one of said members being movable with respect to the coöperating member, automatically-operative means tending to apply a constant shifting movement to said 15 movable member, and manually-operable latch means for normally holding said movable member against movement.

4. A machine of the class described comprising two members one of which constitutes a work-support and the other a tool-support and one of said members being mounted to swing with respect to the companion member, spring-operative means tending to apply a shifting force to said 20 swinging member, and means for normally holding the swinging member against movement.

5. A machine of the class described comprising a swinging tool-support, automatically-operative means tending at all times to swing said support, and means for normally holding said tool-support against movement.

6. A machine of the class described comprising a swinging tool-support, spring-operated means tending to swing said support, and means for normally holding said support against movement.

7. A machine of the class described comprising a slide, a movable support on said 50 slide, means tending to operate said movable support, and means on the slide for normally holding the support against movement.

8. A machine of the class described comprising a slide, a swinging support on said slide, automatically-operative means on the slide tending to constantly shift the support, and means also on the slide for normally holding the support against movement.

60 9. A machine of the class described com-

prising a swinging arm provided with a toothed member movable therewith and a spring-operated rack engaging said toothed member.

10. A machine of the class described comprising a swinging arm, a shaft serving as a pivot for said arm, a spindle carried by the arm, driving connections between the shaft and the spindle, and automatically-operative means tending constantly to swing said arm 65 into an inoperative position.

11. A machine of the class described comprising a swinging arm, spring-operated means tending constantly to shift said arm, and manually-operable latching means for 70 normally holding the arm against movement.

12. A machine of the class described comprising a slide, a swinging arm supported by said slide, a toothed member carried by said 80 arm, a spring-operated rack on the slide, co-operative with said toothed member, and a latch on the arm for engaging the slide.

13. A machine of the class described comprising a slide, a swinging arm supported by said slide, a toothed member carried by the arm, a rack the teeth of which mesh with those of said toothed member, the slide having a passage to receive said rack, a spring in said passage bearing at one end against 90 the rack, the passage having a plug against which the spring also bears, and means for normally preventing swinging movement of said arm.

14. A machine of the class described comprising a swinging tool-support, a slide carrying said tool-support, a spring-operated member for applying a constant shifting force to said swinging tool-support, and a yieldable latch carried by the arm and 100 adapted to engage the slide to prevent movement normally of said arm.

15. A machine of the class described comprising a slide, an arm supported for swinging movement by said slide, a spring-operated plunger on the slide for normally applying a swinging force to said arm, a latch slidably carried by the arm, a spring acting against the latch to normally move the same toward its operative position, the spring being carried by said arm and the latch having 105 a rack, and a pinion supported by said arm for operating the rack and thereby the latch.

In testimony whereof I affix my signature in presence of two witnesses.

BENGT M. W. HANSON.
